DESIGN FOR A WRENCH

Norris F. McNaught, Chicago, Ill., assignor to
Duro Metal Products Company, Chicago, Ill., a
corporation of Illinois

Application January 18, 1937, Serial No. 67,115

Term of patent 7 years

To all whom it may concern:

Be it known that I, Norris F. McNaught, a citizen of the United States, residing at Chicago, in the county of Cook and State of Illinois, have invented a new, original, and ornamental Design for a Wrench, of which the following is a specification, reference being had to the accompanying drawing, forming part thereof.

Fig. 1 is a front elevational view of a wrench embodying my new design;

Figs. 2 and 3, respectively, are side and rear elevational views of the same; and

Figs. 4 and 5, respectively, are cross sectional views taken on the lines 4—4 and 5—5 of Fig. 1.

I claim:

The ornamental design for a wrench as shown.

NORRIS F. McNAUGHT.
